Attest:

UNITED STATES PATENT OFFICE.

JAMES R. STONE, OF BONE GAP, ILLINOIS.

WAGON-BED LIFTER.

SPECIFICATION forming part of Letters Patent No. 247,706, dated September 27, 1881.

Application filed July 28, 1881. (No model.)

To all whom it may concern:

Be it known that I, JAMES R. STONE, a citizen of the United States, residing at Bone Gap, in the county of Edwards and State of Illinois, 5 have invented certain new and useful Improvements in Wagon-Bed Lifters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in wagon-body lifters, and has for its object to furnish a convenient mode of removing a wagon-body in order to replace it with a different body, or for any other reason, all of which will be hereinafter described, and pointed out in the claims.

It consists in arms supporting loops and provided with bearings at or near their middles, placed by means of their bearings on gudgeons on the ends of cross-bar of T-lever parallel to each other and at right angles to the said cross-bar, the whole being operated by the T-lever, as hereinafter more fully set forth.

It consists, further, in having the spindles of the arms formed with stems, which fit in sockets in or by other suitable means to the end cross-bar and adjustable therein, thus rendering the lifter suitable for wagon-bodies of different lengths.

It consists, further, in having the stems of the adjustable spindle formed with a ratchet-bar the teeth of which are engaged by a spring catch or pawl fixed to the cross-bar, so that the adjustable spindle may be held in any position in or out of the socket, as may be desired.

40 In the drawings, Figure 1 is a plan, and Fig. 2 is a side view, of my improved wagon-body lifter; and Fig. 3 shows details of my adjustable spindle.

a is a T-shaped lever composed of the main shaft a' and the cross-bar a². It may be braced, as shown, by bars a⁴ a⁵. The shaft a is fulcrumed at proper point to give suitable leverage to the arm a⁶.

I have shown my lever supported on an intermediate cross-bar properly journaled; but it will be readily understood that it could be sup-

ported by connection with an overhanging rope or pivoted on an upright post, or in other ways not necessary to mention here. The preferable manner of support is to fulcrum the lever on the rotating-bar a⁷ and have the ends of said bar journaled in the sides of the wagon-house.

a² is the cross-bar, having longitudinal sockets a³ a³ formed in its ends. b³ b³ are spring-bars, each having one of its ends made fast to the cross-bar a², and its other end extended outward toward the gudgeon and bent down through suitable hole or slot to engage the ratchets of stem b², as shown, and having formed upon its top a loop, by which the point may be raised clear of the ratchets.

b b are the spindles, each formed with the gudgeon b' and the stem b². The stem b² is fitted to enter the socket a³ of the cross-bar a², and is about the length of said socket. It has formed on one of its sides the series of ratchets or notches which are intended to be caught and held by the point of spring-stop b³. A series of these notches are provided, so that the spindle can be drawn out to and be held in any desired position in order to adapt the device to wagon-bodies of different lengths. The junction of the gudgeon with the stem forms a shoulder, which serves to prevent the carrying-arm c from sliding back on the spindle and to retain it on the gudgeon between the said shoulder and the linch-pin b⁴.

c c are arms provided with bearings at or near their middles, and having the ropes c' c' made fast to them at or near their ends, so as to form a loop, as shown. These ropes pass through the arms c c, and are held on the opposite side thereof by knots or other suitable means, and may be readily lengthened or shortened, as desired.

The bars c c are placed on the gudgeons b' b' parallel to each other and at right angles to the cross-bar a², and have a free rocking motion in the direction of their length.

In the operation of my device in raising a wagon-body the free rocking motion of the carrying-arms c will permit the wagon-body to retain its horizontal position as the cross-bar a² is raised.

The operation of my device is as follows: The loops c' c' are adjusted under opposite ends of the wagon-body and pressure is applied to

the lever-arm a^6 , when the body will be raised clear of the running-gear and will be kept in a horizontal position by the bearing furnished the carrying-arms $c c$, as described.

5 Having thus described my invention, what I claim, and desire to secure by Letters Patent, is—

1. In a wagon-body lifter, the carrying-arms $c c$, provided with bearings at or near their mid-
10 dles and arranged to support the loops $c' c'$, and supported on gudgeons on the ends of cross-bar a^2 of the T-shaped lever a , parallel to each other and to the main shaft a' and at right angles to the cross-bar a^2 , substantially as set forth.

15 2. In a wagon-body lifter, the spindles $d b$, having stems $b^2 b^2$, fitted in sockets in or by

other suitable means to the cross-bar b' , and adjustable in or out in order to adapt them to wagon-bodies of different lengths, substantially 20 as set forth.

3. The combination, with the adjustable spindles $b b$, having one side of their stems formed with ratchet-bars, of the springs b^3 , fixed to the cross-bar a^2 , and bent to form the catch 25 or pawl arranged to engage the teeth of the ratchet, substantially as set forth.

In testimony whereof I affix my signature in presence of two witnesses on this 16th day of July, 1881.

JAMES RILY STONE.
